[57] CLAIM

The ornamental design for a spray misting fan and bottle, as shown and described.

DESCRIPTION

FIG. 1 is a perspective view of a spray misting fan and bottle showing our new design;

FIG. 2 is a front elevational view thereof;

FIG. 3 is a top plan view of the present design;

FIG. 4 is a bottom view of the spray misting fan and bottle according to the present design;

FIG. 5 is a left side view of the present design;

FIG. 6 is a rear elevational view;

FIG. 7 is a right side view which is a mirror image of the left side view; and,

FIG. 8 is an exploded view illustrating the threaded engagement between upper and lower halves of the bottle portion of the spray misting fan and bottle according to the present design.
